PROCESS OF PREPARING A DETERGENT COMPOSITION

Edwin S. Garverich, Upper Darby, and William L. Martin, Philadelphia, Pa., assignors to The Pennsylvania Salt Manufacturing Company, Philadelphia, Pa., a corporation of Pennsylvania

No Drawing. Application December 4, 1942,
Serial No. 468,168

2 Claims. (Cl. 252—116)

1

This invention relates to improved laundry detergent and break compositions and to their preparation.

Particularly the invention relates to the preparation of detergent compositions containing ingredients which will react with one another.

For example, detergent compositions made by mixing together alkali metal silicates such as sodium orthosilicate, sodium sesquisilicate and sodium metasilicate; hydrophilic colloids, such as bentonite; alkali metal phosphates such as the sodium orthophosphates, the sodium pyrophosphates and sodium metaphosphate; and fatty acid containing oils such as tall oil, or fatty acid ester oils, such as palm oil, have been found by us to be particularly effective when mixed in certain proportions and order under certain conditions.

According to this invention laundry detergent and break compositions are prepared from materials such as above mentioned in such manner that substantial reaction between the alkaline materials and the clay, on the one hand, and alkaline materials and fatty acid containing oil on the other, is prevented.

An important characteristic of an embodiment of this invention resides in the order of mixing the components. A composition consisting of an alkali metal subsilicate, an absorptive clay, an alkali metal phosphate and fatty acid is prepared so that no appreciable reaction will take place between the fatty acid and silicate, or between the clay and the silicate. If these reactions are not prevented, the properties of the product will be impaired, the quality will be relatively poor, and the oil will be saponified by reaction with the alkali metal silicate. This is accomplished by adsorbing or absorbing substantially all of the fatty acid in the clay before adding the alkali metal subsilicate. In this manner substantial reaction of the fatty acid or oil and silicate and the clay and silicate is prevented.

Control of moisture is essential during processing if reaction between the alkali metal subsilicate and the clay is to be controlled. One control is exercised by the premixing of the oil and bentonite, already described, thereby preventing the formation of free moisture through saponification when the alkalies are added to the mix. An advantage of preventing saponification is that it will then occur when the composition is added to water and this is known to produce a greater cleaning effect. "When soap is formed in the wash wheel, a greater cleaning effect is produced at the moment of neutralization

2

than when an equivalent quantity of soap is added."—(E. Meissner Deut. Wollen-Gewerbe 70, 381—2, 1938.)

Another control of moisture can be effected by pre-drying the bentonite or absorptive clay.

A further reaction control is carried out by cooling during the mixing of the constituents as well as cooling the final product immediately after its preparation. Cooling during mixing removes the heat of any reaction which does occur preventing an accelerated and uncontrollable reaction. Cooling of the product, as formed, will arrest any reaction then taking place thereby further preventing heat generation from promoting reaction between the unreacted clay and alkali metal subsilicate and between the oil and alkali metal subsilicate.

As stated, it is important that the tall oil or fatty acid be mixed with the absorptive clay before the alkali alkali subsilicate is added. If desired, it is within the scope of the invention to effect mixing in any other order. In such case, more cooling to prevent reaction will be necessary or the product will not have the same quality as when prepared according to the preferred mixing order.

By first mixing the clay and oils there are obtained the following advantages:

1. Better and more uniform distribution of the oils.
2. Prevention of an appreciable reaction between the clay and alkali subsilicate.
3. Retardation of saponification of the fatty acids until the composition is added to water, for example in the laundry wash wheel.
4. A uniform and better appearing product.

The preparation of the composition of this invention is generally carried out by feeding the oils, preferably as an atomized spray, into a mixer in which the clay is being agitated. After addition of the oils, the alkali metal subsilicates and alkali metal phosphates are added. The mixer is so arranged that sufficient heat dissipation will occur to prevent a substantial rise in temperature and so that compression and compaction of the ingredients will be at a minimum. After the ingredients have been thoroughly mixed, the product is cooled, preferably with agitation, to ensure substantially complete arresting of any reaction which may be taking place and to break up any agglomerates or nodules which may be in the product. This step may be carried out in a flight conveyor equipped with cooling jackets or in a cooled rotary tube or in any other manner.

The following examples will serve to illustrate the compositions of the invention.

Parts by weight	
1	
Bentonite (200 mesh)	40
Tall oil (refined)	15
Sodium orthosilicate	35
Trisodium phosphate (monohydrate)	10
2	
Bentonite	40
Tall oil (crude)	7.5
Red oil (oleic acid)	7.5
Sodium orthosilicate	35
Trisodium phosphate (monohydrate)	10
3	
Bentonite	45
Tall oil	15
Sodium orthosilicate	35
Trisodium phosphate	5
4	
Bentonite (200 mesh)	40
Tall oil (refined)	15
Sodium orthosilicate	35
Tetrasodium pyrophosphate	10
5	
Bentonite (200 mesh)	35
Tall oil (refined)	15
Sodium metasilicate	40
Trisodium phosphate (monohydrate)	10
6	
Bentonite	45
Tall oil (refined)	15
Sodium sesquisilicate	35
Trisodium phosphate	5

The relative quantities of ingredients employed in the composition will vary somewhat depending upon conditions of use.

The bentonite or adsorptive clay may be from 25% to 75% of the mixture.

The quantity of oils used may be varied. From about 5% to 20% will yield effective detergent results. Greater quantities are not generally recommended and amounts in excess of about 25% lead to a material difficult to process and to such general disproportions that the composition will not yield good results. Obviously, as shown in Example 2 some of the fatty acids may

be added in the form of Red oil or any other fatty acid or fatty acid containing material which can be admixed as herein described and which is saponifiable.

5 The alkali metal subsilicate can likewise be varied. The use of about 25%-35% is generally sufficient. Quantities greater than about 45% are not recommended as this leads to production trouble, disproportionate relationship between alkali and colloid, excessive pH values in the break operation and, therefore, poor results.

Wherever "alkali metal silicate" is used in the specification those compounds or mixtures are encompassed within the term which have a ratio of Na_2O to SiO_2 of 1 to 1 or greater. This includes sodium metasilicate, the subsilicates sodium sesqui- and sodium orthosilicate, and mixtures of caustic and silicates in which the over all ratio of Na_2O to SiO_2 is 1 to 1 or greater.

10 15 20 The alkali metal phosphate content may be doubled, or even tripled, but use of less than about 5% will lead to serious losses in suds stability and level. It is important that a phosphate of low moisture content be used for good results.

25 We claim:

1. The process of preparing a detergent composition containing by weight 5%-25% tall oil, 25%-45% of an alkali metal subsilicate capable of saponifying said oil, at least 5% of an alkali metal phosphate and 25%-75% of bentonite which comprises mixing the oil and clay to cause absorption of the oil by the clay and then admixing the alkali metal subsilicate; and wherein at least the admixing of the subsilicate is effected during cooling; and further cooling the product formed.

2. The process of preparing a detergent composition containing about 5 to 25 parts by weight of a fatty acid oil, about 25 to 45 parts by weight 40 45 of an alkali metal subsilicate capable of saponifying said oil, at least 5% of an alkali metal phosphate and about 25 to 75 parts by weight of an absorptive clay having colloidal properties which comprises mixing the oil and clay to cause absorption of the oil by the clay and then, while cooling, admixing the subsilicate and cooling the product formed.
